APPARATUS FOR MAKING STEREOTYPE PLATES.

APPLICATION FILED SEPT. 9, 1905.

2 SHEETS—SHEET 2.

UNITED STATES PATENT OFFICE.

HERMAN WINTER, OF NEW YORK, N. Y., ASSIGNOR TO F. WESEL MANUFACTURING COMPANY, OF BROOKLYN, NEW YORK, A CORPORATION OF NEW YORK.

APPARATUS FOR MAKING STEREOTYPE-PLATES.

No. 852,642.

Specification of Letters Patent.

Patented May 7, 1907.

Application filed September 9, 1905. Serial No. 277,757.

To all whom it may concern:

Be it known that I, HERMAN WINTER, of the borough of Brooklyn, of the city of New York, in the State of New York, have invented certain new and useful Improvements in Apparatuses for Making Stereotype-Plates, of which the following is a specification, reference being had to the accompanying drawings forming a part hereof.

10 In the use of stereotype plates with a curved cross-section, that is stereotype plates having a substantially semi-cylindrical shape, it is often advantageous to have the plates comprise a segment of more than 180 degrees or in other words to have the cylindrical plates greater in extent than that of a semicircle. For by such means it not only happens that a wider range in the size of plates that can be manufactured by a particular machine, is permitted, but the form of the plates which comprise a segment greater than 180 degrees, particularly adapts them for use in certain kinds of presses.

Heretofore with a semi-cylindrical drag 25 and a correspondingly shaped cope, which was adapted to be inserted into and withdrawn from the open side of the drag, no stereotype plates, as is obvious, could be made with a curvature greater than 180 degrees.

It is accordingly one of the objects of the present invention to provide an apparatus of this general character in which it will be possible to cast stereotype plates comprising 35 a segment greater than 180 degrees.

Other objects of the invention are to improve such apparatuses in different details all of which will be referred to hereinafter and in connection with the drawings in 40 which a practical apparatus embodying the invention is shown.

In said drawings Figure 1 is a view in side elevation of this apparatus, Fig. 2 is a view in front elevation, Fig. 3 is a view in side elevation with the casting box partly in section and shown in its vertical position, Fig. 4 is a view in front elevation of the casting box showing the two parts of the cope drawn together or collapsed, Figs. 5 and 6 are detail 50 sectional views of a portion of one of the clamps for securing the cope to the drag, Figs. 7 and 8 are detail views of the head

gage, and Fig. 9 is a detail broken view showing one of the pivoted side gages and the strip to which it is pivoted.

55

The casting box A, as usual, may be provided with trunnions a and pivoted upon a frame B, whereby it may assume a horizontal position for the insertion of the matrix and for the removal of the finished plate or a vertical position for the casting of the plate. For holding the casting box in a horizontal position, one or more bell crank levers b may be provided pivoted to the frame B and means such as a foot press b' may also be provided to disengage the levers b from the casting box said levers being normally held in their engaging position by a spring b². Stops b³ and b⁴ are preferably placed upon the frame B so as to assist in supporting and 70 steady the casting box when it is in its horizontal and vertical positions respectively.

The cope C of the casting box, is pivoted to the rear end of the drag at c and is provided with a weight d and a cord d' which latter is secured thereto and runs over a pulley d² back of the casting box, whereby the cope can be conveniently manipulated upon its hinge by the operator.

75

The segment comprised by the drag, as will be seen from Figs. 2 and 4, is somewhat greater than 180 degrees, the precise extent, however, over 180 degrees being unimportant.

In order to permit the cope to be readily inserted into and withdrawn from the opening in the upper side of the drag, said cope is split lengthwise and thus comprises two parts or sides, c' and c², which are arranged so as to be readily collapsed and expanded, as re-

80

quired. Thus, when the cope is collapsed, it may be readily moved into and out of the drag, and after the cope has been moved into the drag it may be expanded so as to occupy the proper position with reference to the sides 95 of the drag and the matrix m for casting.

For this purpose the two sides of the cope c' and c² are preferably pivoted, as shown in Fig. 3, to a central support c³ for the cope, said support being pivoted or hinged at c, as already stated and having toward its forward end a cross bar c⁴ which, through means such as adjustable screws c⁵, is supported on the drag, near the forward end thereof. As

95

100

shown the cope support c^3 has two pins c^6 upon which the sides c^1 and c^2 are pivoted.

In order to expand and collapse the two sides of the cope, they may be connected at 5 the top by means of links e to a crank e' fast upon a shaft e^2 rotatable in the cope support, a lever e^3 being provided whereby the shaft e^2 may be rotated at will and the cope sides expanded or contracted as the case may be. 10 Preferably the shaft e^2 extends substantially the length of the cope and is connected to the sides of the cope in the manner described above, at both ends thereof.

When the cope has been inserted into the 15 drag and is extended as just described, it is firmly secured to the drag by clamps f , of which there are preferably four, one on each side near the front and near the rear of the casting box. Each of these clamps is mounted 20 loosely on a shaft f' which has an eccentric bearing or pivot f^2 to which a handle f^3 is secured. The clamps are adapted to engage lugs f^4 on the cope, and when they have been brought to engage said lugs, the handles f^3 are moved so as to rotate the shafts f' upon their eccentric pivots whereby said 25 clamps are tightened against the lugs.

Fig. 4 shows the position of the clamps f and the handles f^3 before the clamping and 30 Fig. 2 the position of these parts after the clamping. Furthermore each of the clamps is provided with a spring f^5 which encircles its pivot f^2 and one end of which spring engages the clamp while the other end engages the shaft upon which the clamp is pivoted. 35 The spring thus normally tends to hold the clamp back from its lug in a substantially vertical position, as shown in Fig. 4, whereby it will not be in the way as the cope is moved 40 into and drawn out of the opening in the top of the drag.

The apparatus is provided, as usual, with a head gage g , which may comprise a band with conveniently formed handles and adapted to 45 be sprung into the rear end or head of the drag, and side gages h , which in the present case are pivoted to a long strip h' , which is screwed onto either side of the drag. The matrix is secured in the drag, as usual, by 50 means of the gages, and the pivoting of the side gages makes the operation of securing and releasing the matrix particularly convenient.

In addition to the head and side gages 55 there is provided what will be referred to as a split gage, which in the present case, consists of a long bar or strip k adapted to fit in tightly and in a lengthwise position between the cope C and the matrix m . This gage is 60 provided so that plates of different sizes may be cast as desired. In order to hold this gage in position and to move it about from one part of the casting box to another part, a spring clamp handle is provided. Said 65 spring clamp handle may comprise an exten-

sion on the bar or strip k projecting somewhat beyond the end of the casting box and a member k^1 pivoted thereto with a projection k^2 upon the inner end thereof which fits in a small groove behind a shoulder k^3 which runs 70 around the front end of the drag. A spring k^4 is provided between the member k^1 and the extension of the strip k whereby the projection k^2 is held tightly in said groove. When it is desired to change the position of the 75 split gage in the casting box the handle is grasped by the operator and the member k^1 is moved against the action of the spring k^4 thus withdrawing the projection k^2 from the groove behind the shoulder k^3 . When the 80 gage has been properly adjusted, the operator lets go the handle and the gage is automatically fastened, as will be clear from Fig. 3 of the drawing. It will be understood that the 85 casting operation is performed when the casting-box is in its vertical position, as shown in Fig. 3, and after the plate has been cast the box is tilted to its horizontal position, as shown in Fig. 1, the cope being collapsed and moved through the front end of the drag, or, by rotating it about one-quarter, it may be 90 removed through the opening in the top of the drag.

Various changes may be made in the construction of the apparatus herein shown and described without departing from the invention, and the scope of the invention is accordingly not limited to the embodiment of the improvements herein specifically referred to. 95

I claim as my invention:

1. In an apparatus for making stereotype plates, the combination of a drag having a longitudinal opening less than its diameter and a cope adapted to be withdrawn through 105 said opening.

2. In an apparatus for making stereotype plates, the combination of a drag having a longitudinal opening less than its diameter, a split cope adapted to be withdrawn through 110 said opening, and means for collapsing said cope.

3. In an apparatus for making stereotype plates, the combination of a drag comprising a cylindrical segment of more than 180° and 115 provided with an opening extending longitudinally thereof, and a split cope adapted to be inserted and withdrawn through said opening, whereby the cope can be inserted and withdrawn from the drag.

4. In an apparatus for making stereotype plates, the combination with a drag having a longitudinal opening less than its diameter, of a two-part cope hinged together, and means arranged between the free edges of said cope 120 to collapse the same.

5. In an apparatus for making stereotype plates, the combination with a drag having a longitudinal opening less than its diameter, of a two-part cope hinged together, means to 125

support the cope in the drag, and means arranged between the free edges of said cope to collapse the same.

6. In an apparatus for making stereotype plates, the combination of a curved drag, a two-part cope, means to support the cope in the drag, the two parts of the cope being hinged to the supporting means, a shaft rotatable on said supporting means, links interposed between said shaft and the two parts of the cope, and a lever secured to the shaft.

7. In an apparatus for making stereotype plates, the combination with a drag having a longitudinal opening less than its diameter, of a two-part cope hinged together, supporting means to which said cope is pivoted, means for withdrawing said cope from the drag through said opening, and means to collapse said cope.

8. In an apparatus for making stereotype plates, the combination with a drag having a longitudinal opening less than its diameter, of a two-part cope hinged together, means to support the cope in the drag, the two parts of the cope being pivoted to the supporting means, and means arranged between the free edges of the parts of said cope to swing the parts of the cope upon their hinges.

9. In an apparatus for making stereotype plates, the combination of a curved drag, a cope therefor, an adjustable gage adapted to fit between the matrix and the cope and to project from the drag, and means substantially as described to clamp the gage in position.

10. In an apparatus for making stereotype plates, the combination of a curved drag having a shoulder k^3 on the front thereof, a cope, an adjustable strip or split gage adapted to fit between the matrix and the cope and having its end projecting from the drag, and a clamp on said gage fitting over said shoulder and adapted to hold the gage in adjusted position.

11. In an apparatus for making stereotype plates, the combination of a curved drag, a

cope split lengthwise to form two separate sides, the two sides being hinged together, and means arranged between the free edges 50 of said sides to collapse and expand the cope.

12. In an apparatus for making stereotype plates, the combination of a drag comprising a cylindrical segment of more than 180 and less than 360 degrees, whereby a longitudinal opening is provided in said drag, and a cope adapted to be withdrawn through said opening.

13. In an apparatus for making stereotype plates, the combination of a drag comprising 60 a cylindrical segment of more than 180 and less than 360 degrees, whereby a longitudinal opening is provided in said drag, and a cope comprising a cylindrical segment of substantially the same number of degrees 65 and adapted to be inserted and withdrawn through said opening.

14. In an apparatus for making stereotype plates, the combination of a drag comprising 70 a cylindrical segment of more than 180 and less than 360 degrees, whereby a longitudinal opening is provided in said drag, and a two-part cope hinged together and adapted to be inserted and withdrawn through said opening, said cope comprising a cylindrical 75 segment of more than 180 and less than 360 degrees.

15. In an apparatus for making stereotype plates, the combination of a curved drag, a cope comprising two parts hinged together, 80 and means arranged between the free edges of said parts to collapse and expand the cope.

16. In an apparatus for making stereotype plates, the combination of a curved drag, a cope comprising two parts hinged together, 85 and means arranged between and pivoted to the free edges of said parts to collapse and expand the cope.

This specification signed and witnessed this 8th day of Sept. A. D., 1905.

HERMAN WINTER.
